Filed Jan. 23, 1967, Ser. No. 5,517

Term of patent 14 years

(Cl. D34—5)

FIG. 1

FIG. 2

FIGURE 1 is a top plan view of my new design for a pin placement indicator board to be used in association with golf courses.

FIGURE 2 is a side elevation thereof.

Other sides are the same as that shown.

The essential features of my design reside in the full line portions shown with the various conventional flag pieces in broken lines to show the indicator pieces.

I claim:

The ornamental design for pin placement indicator board for golf courses, as shown and described.
